CLAIM

The ornamental design for a food conveyor as shown and described.

DESCRIPTION

FIG. 1 is a top, front and right side perspective view of a food conveyor showing my new design;
FIG. 2 is a top, rear and right side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is a front, top and right side perspective view showing the food conveyor in a state of use;
FIG. 10 is a rear, top and right side perspective view showing the food conveyor in another state of use; and,
FIG. 11 is an enlarged view of portion 11 in FIG. 1.
The broken lines in the drawings illustrate portions of the food conveyor which form no part of the claimed design.

1 Claim, 11 Drawing Sheets
